UNITED STATES PATENT OFFICE.

JOHN M. FAULCONER, OF SILVER SPRING, MARYLAND.

PORTABLE GASOLENE-MEASURING DEVICE.

1,368,494.

Specification of Letters Patent. Patented Feb. 15, 1921.

Application filed March 27, 1920. Serial No. 369,216.

To all whom it may concern:

Be it known that I, JOHN M. FAULCONER, a citizen of the United States, residing at Silver Spring, in the county of Montgomery and State of Maryland, have invented certain new and useful Improvements in Portable Gasolene - Measuring Devices, of which the following is a specification.

This invention relates to liquid measuring appliances for liquid storage tanks, and pertains especially to a portable measuring device adapted for transferring gasolene, in measured quantities, from a supply wagon tank to an automobile service station tank.

15 The object of the invention is to provide a simple and comparatively inexpensive portable device in which successive injection and ejection of liquid into and from a pair of measuring chambers is automatically controlled by a compound valve at the bottom of a partition separating said chambers, said valve being operated by a rod extending through a liquid induction pipe which intersects the partition and is connected with the valve.

20 A further object of the invention is to provide in a liquid measuring device, a single valve having such construction and location relative to a centrally divided can or casing as to cause one side of the can to fill during the emptying of the other side.

25 A still further object of the invention is to provide a liquid measuring can having a central vertical partition dividing the can into two liquid measuring chambers having their only inlet and outlet through a valve centrally under the partition, such valve being operated by a valve rod extending through a pipe central of the partition for conducting the liquid to the valve so that the valve shall control simultaneous passage of the liquid through the valve into and out of the chambers formed by the partition.

30 Various other objects, advantages and improved results are attainable in and by the special construction and arrangement of parts, as will be hereinafter disclosed.

35 In the accompanying drawings forming part of this application:—

Figure 1 is a perspective view showing the application of the measurer to a protruding filling pipe of an underground gasolene storage tank.

40 Fig. 2 is a central vertical sectional view partly broken away.

Fig. 3 is a cross section taken on the dotted line A—A, Fig. 2.

Fig. 4 is an enlarged detail vertical section of the compound valve. 60

Fig. 5 is a detail cross section taken on the dotted line B—B, Fig. 4. Fig. 6 is a detail view of part of the partition.

Fig. 7 is a detail view showing positions of valve handle. 65

The same reference characters denote the same parts throughout the several views of the drawings.

In carrying out my invention, I preferably employ a cylindrical can or container 1, composed of galvanized iron or sheet metal having ordinary band braces 2, a pair of hinged top lids or covers 3, and a funnel or cone shaped bottom 4 having an inner valve housing 5 from which projects 70 a tubular casing 6 extending centrally through the can 1 through the top 7 thereof. A coupling 8 is secured to the tube 6 and affords means for attaching a hose or pipe 9 leading from a wagon gasolene tank 80 or other container. The cylinder or can 1 is divided centrally into two gasolene chambers 10 and 11 by means of vertical partition members 12 joined to and extending from the pipe casing 6 to the wall of the 85 can so that the casing intersects the partition centrally and also forms a partition member. The functions of the casing 6 being essential in that it affords means for joining the partition members central of the 90 can, forms a housing and protection for the gasolene pipe, and affords means for withdrawal of the valve, valve rod and the gasolene pipe 13 from the can for cleaning, repair or renewal of the parts as may be occasioned by long usage. 95

The gasolene pipe 13 is connected with the upper open end of the compound valve 15 by a coupling head 14, and said pipe extends through the casing 6 into the coupling 8 so as to receive gasolene from the connecting pipe 9. The valve has a central longitudinal partition 16 dividing the valve into upper and lower members 17 and 18, respectively. The lower member 18 or bottom of the valve is open for the discharge of gasolene therethrough, and such opening is desirably larger in diameter than the induction pipe 13, and is the same size as that of a discharge pipe 19 which is secured 100 to and projects from the base member 20 of the valve, and said projecting pipe is 110

adapted to be inserted into an ordinary nozzle or pipe 21 projecting from a storage tank. The upper member 17 of the valve has a port 23 always in open communication 5 with the upper open end of the valve, but is opened and closed with respect to the ports 24 and 28 in the valve casing 25 by operating a valve rod 33, hereinafter particularly referred to. The lower valve 10 member 18 has a like construction, except its port 27 is in reversed position to that of the port 23, and said port is opened and closed with respect to the ports 28 in the valve casing, by operating the valve rod. 15 The valve body or casing 25 has opposite lateral extensions 29 through which the casing ports 24 and 28 extend, and these ports are provided with open screw bushings 30 for detachably securing the casing 25 to 20 the housing 5, and for making a fluid tight connection so as to afford permanent communication between the ports 24 and 28 and the chambers 10 and 11. The eduction end of the valve casing 25 is provided with 25 a screw cap 31 having a conically flaring flange 32 fitting the conical bottom of the can 1. The valve rod 33 has, preferably, a square end 34 fitting a like socket 35 central of the valve partition 16, and said rod 30 extends through the induction pipe 13 and projects through the coupling 8, where the upper end of the rod is secured by suitable means and is operated by a hand lever 36. The can is provided with suitable handles 35 37 for transporting and hanging the can. The chambers are provided with sight tubes 38, and a filtering screen 39.

In order to prevent overflow of the chambers 10 and 11, by reason of the valve being left open too long during a tank-filling operation, apertures or fluid ducts 39^a are made through the partition members adjacent to the top edge thereof and above the limit of capacity, as five gallons, of the 45 chambers. These ducts also permit the passage of fluid from one chamber to the other when the valve is closed to both chambers until the fluid supply is cut off from the can.

50 The operation in detail is as follows:— The hose 9 being attached to a gasoline tank of a truck or wagon, gasoline is conveyed by said hose through the coupling 8 into the induction pipe 13 while the valve 55 is closed as indicated by the "closed" position of the handle 36 shown in Fig. 7. Then the handle is reversed or turned to either of the "open" positions as shown in Fig. 7 which turns the valve into position to admit 60 passage of gasoline therethrough as by way of the ports 23 and 24 into the chamber 11 so as to fill this chamber to its capacity, for example, five gallons which is indicated by the gage tube of this chamber, 65 thereupon the handle is reversed or turned

to the other "open" position whereby the valve port 23 is closed and the other of the ports 24 leading to the chamber 10 is opened for discharging gasoline into the chamber 10 while the measured gasoline is 70 being discharged from the chamber 11 through its port 28, and the discharge pipes 19 and 21, into a storage tank. This operation is repeated for any desired amount of liquid to be measurably transferred or 75 stored.

It will be seen that the valve, the valve rod and the induction pipe may be withdrawn through the bottom of the can by merely removing the bushing, the cap 31 80 and the coupling 8, and releasing the upper end of the valve rod; that the hinged lids afford separate access to the chambers, and that the can handles afford convenient means for transporting, and for hanging the 85 can when not in use.

The top and bottom of the valve being permanently open respectively to the induction and eduction valve pipes, movement of the valve rod will open one of the ports 90 24 and one of the ports 20 so as to admit gasoline into one of the chambers during the discharge of gasoline from the other chamber.

I do not wish to be understood as confining my invention to any particular size, material and capacity, nor in the application thereof, but reserve the right to make such changes and variations therein and in the application thereof, as may not be inconsistent with the appended claims. 95

Having thus described my invention what I claim as new and desire to secure by Letters Patent is:—

1. In a gasoline service station appliance, 105 a measuring can having an intake end and an outlet end, a central partition dividing the can vertically into two measuring chambers, a valve in the bottom of the can, an induction pipe secured to and opening into 110 the valve, said pipe extending central of the partition and terminating in the said intake end, and a valve rod attached to the valve and extending through said pipe and through said intake end, one movement of 115 said rod placing the valve for filling one of said chambers and for emptying the other chamber during such filling.

2. In a liquid measuring device of the character described, a container divided 120 centrally into two chambers by a vertical partition, a valve for inducting the liquid into one chamber and discharging the liquid from the other chamber during said induction, an induction pipe attached to and opening into the valve, said pipe extending vertically and centrally through the partition, and a valve rod attached to the valve and extending through the pipe. 125

3. In a liquid measuring device of the 130

- character described, a container having a central vertical partition dividing the container into two separate chambers, a valve housing centrally under the partition, a tubular casing projecting from the housing and forming the central part of the partition, a valve working in the housing, an induction pipe extending through the said casing and connecting the valve with an intake 5 of the container, and a valve rod attached to the valve and extending through the pipe for placing the valve so as to fill one of the chambers during the emptying of the other chamber.
- 10 4. In a liquid measuring device of the character described, a container having a central valve housing in the bottom thereof, a tube extension of the housing joined with the top of the container, partition members 15 branched from the tube and dividing the
- 20

container into chambers, a compound valve within said housing, an induction coupling, an induction pipe within the tube and attached to the valve and to the coupling, and a valve rod extending through the pipe and 25 the coupling.

5. In a device of the character described, a container, a valve casing, a valve, a valve housing formed within the bottom of the container and having lateral openings cor- 30 responding with the casing ports, and open bushings extending through the wall of the housing and screwing into said ports for attaching the casing to the housing.

In witness whereof I hereunto set my 35 hand in the presence of two witnesses.

JOHN M. FAULCONER.
